REMOTE CONTROL SYSTEM

Paul H. Crago, Wilkinsburg, Pa., assignor to The
Union Switch & Signal Company, Swissvale,
Pa., a corporation of Pennsylvania

Application February 23, 1933, Serial No. 658,066

16 Claims. (Cl. 246—3)

My invention relates to remote control systems; and particularly to remote control systems for controlling railway switches from a remote point and for communicating to said remote point the position of said switches and other information, such for example, as the position of trains in the vicinity of the railway switches.

In my copending application, Serial No. 631,041, filed August 30, 1932, for Remote control systems, I have described a system of control wherewith a two-way control is accomplished between two remotely located stations over a single pair of line wires. The control is effected by providing a pair of loop circuits at each of the two stations, each loop circuit being adapted to pass current in a given direction only; and by supplying impulses of current of opposite polarity to the line circuit at time spaced intervals to selectively influence these loop circuits. In this copending application, the specification describes apparatus for governing the operation of a single railway switch and its related signals. The control of the railway switch from one extreme position to the other position is effected by supplying current to the line circuit for only a short predetermined interval, namely, during the release period of a slow release relay. This slow release relay is governed by a push button, and the arrangement is such that for each operation of the push button, the railway switch is operated to the position opposite that which it occupied just previous to the operating of the push button. A feature of my present invention is the provision of novel and improved apparatus wherewith the same general principle of control of my former case is adapted to govern the operation of at least three railway switches; and to indicate the positions of these switches over a single pair of line wires, the line circuit being also available for OS-ing the occupancy of a plurality of different track sections located in the vicinity of the switches. The utility of the arrangement here disclosed is that a material saving in line wires is effected when several railway switches are to be controlled from the same office station, and the occupancy of a number of different track sections is to be indicated at the remote office station. Other features of my invention will appear as the specification progresses.

I will describe one form of apparatus embodying my invention, and will then point out the novel features thereof in claims.

In the accompanying drawings, Figs. 1 and 2,

when taken together, with Fig. 1 at the left, constitute a diagrammatic view of one form of apparatus embodying my invention for controlling the operation of three railway switches; and for OS-ing the occupancy of two track circuits. The apparatus of Fig. 1 is that located at the remote or office station, and the apparatus of Fig. 2 is that located at the field station. While many different arrangements of railway switches to which my present invention may be applied will naturally suggest themselves to those skilled in the art, the specific arrangement here disclosed is that of two derailing switches and one single switch at a grade crossing of two railways, each railway being equipped with a track circuit.

To simplify the drawings as much as possible, I have, in many instances, illustrated a circuit controlling contact remote from the relay winding governing the operation of that contact. In all such instances, the reference character corresponding to the controlling relay is placed just above the contact, and the contact is further given a distinctive individual reference character. The contact is illustrated in the drawings in a position corresponding to the normal position of the relay. For example, the circuit controlling contact of Fig. 2 designated by the reference character 20 is governed by a track relay 6TR to be referred to later, and this front contact is shown closed, inasmuch as the track relay 6TR is normally energized.

In the present application, only the control relays for governing the operation of each railway switch are shown, the operating mechanism and operating circuits being omitted as they form no part of my present invention. For clarity, these control relays are each here designated by a reference character which corresponds to the reference character for the same relay in my aforementioned application, a prefix being added in this instance, however, to designate the associated switch. For a complete understanding of the switch operating circuits, and the manner in which the control relays govern the operating circuits of a railway switch, reference is made to my copending application Serial No. 631,041. It is deemed, therefore, sufficient for the present description to point out specifically the manner of selecting the control relays for each particular switch from the remote office; and then refer only in a general way to the manner in which these control relays function to bring about the operation of the corresponding railway switch. Furthermore, in the present instance, no wayside signals are shown for governing traffic inasmuch

as the control of the wayside signals forms no part of my present invention. The wayside signals may be of any of the standard types, and may be automatically controlled; or they may be controlled by the dispatcher at the remote office by any one of several well known systems.

Referring to Fig. 2, the reference characters X and Y designate two railway tracks crossing at grade. The railway X includes two derailing switches 6 and 7, and a single switch 9 leading to a side track Z. The derailing switches 6 and 7 and the single switch 9 are each operated by a power operating switch mechanism of any one of several types, and which are shown on the drawings only by a symbol commonly used in the art for such purposes. The mechanisms for the switches 6, 7 and 9 are designated by the reference characters 6M, 7M and 9M, respectively. As previously stated, the operating circuits for governing each of these switch mechanisms 6M, 7M and 9M are preferably controlled by three switch controlling relays in the manner described in detail in my copending application, Serial No. 631,041. In Fig. 2, the operating mechanism 6M is governed by the three control relays 6WR, 6RWR, and 6NWR; the mechanism 7M is controlled by the relays 7WR, 7RWR and 7NWR; and in like manner the mechanism 9M is controlled by relays 9WR, 9RWR and 9NWR. In each of these groups of control relays, the WR relay is preferably a polarized relay of the type in which the polar armature when the relay is deenergized, remains firmly held in the position to which it was last moved when the relay was energized; and the RWR and the NWR relays are preferably neutral relays. As illustrated in the drawings, all three relays of a group are normally deenergized.

Referring to the group of control relays for the switch mechanism 6M, the relays 6RWR and 6NWR are governed by two dispatcher controlled relays LGR and RGR to be later described, the relay 6NWR being selected over the normal, or lefthand position of a polar armature 21 of relay 6WR, and the relay 6RWR being selected over the reverse or righthand position of the polar armature 21. When the dispatcher controlled relay LGR is picked up in a manner to be later described, current is supplied from the B terminal of a battery 22 over back contact 23 of relay RGR, front contact 24 of relay LGR, normal position of polar armature 21, winding of relay 6NWR and to a center C terminal of battery 22. In the event polar armature 21 of relay 6WR is in the reverse position, the picking up of the dispatcher controlled relay LGR supplies current to the relay 6RWR over this same circuit. As described in detail in my above-mentioned copending application, relay 6NWR when selected, completes a circuit which is adapted to supply to the winding of relay 6WR current of a polarity that causes that relay to be energized in its reverse position; and relay 6WR when energized in its reverse position, causes the switch mechanism 6M to operate the switch 6 to its reverse position. When the relay 6RWR is selected, it completes a circuit which is adapted to supply to the winding of relay 6WR current of a polarity that causes that relay to be energized in its normal position; and relay 6WR when energized in its normal position, in turn, causes the mechanism 6M to move the switch 6 to its normal position. While only the essential parts of the pickup circuits for the 6NWR and 6RWR relays are shown, it will be under-

stood that the complete circuit for each NWR and RWR relay in connection with the associated WR relay will be the same as shown in my copending application Serial No. 631,041; and hence, the energizing of either relay 6RWR or 6NWR for only a brief interval is sufficient to bring about a full corresponding operation of switch 6.

The relays 7RWR and 7NWR of the control group for switch mechanism 7M are also governed by the dispatcher controlled relays LGR and RGR. In this instance, the energizing of the relay RGR supplies current from the B terminal of battery 22 over the front contact 30 of relay RGR, back contact 31 of relay LGR, winding of relay 7NWR when the polar armature 32 of relay 7WR occupies its normal position and thence to the C terminal of battery 22, or to the winding of relay 7RWR when the polar armature 32 occupies its reverse position and thence to the C terminal of battery 22. Selecting relay 7NWR, completes a circuit for supplying current of reverse polarity to the relay 7WR, and that relay is energized in its reverse position to cause the switch mechanism 7M to operate the switch 7 to its reverse position. Selecting the relay 7RWR completes a circuit for energizing the relay 7WR in its normal position to bring about a normal operation of the switch 7.

The relays 9RWR and 9NWR of the control group for mechanism 9M are also governed by the dispatcher controlled relays LGR and RGR, the circuit in this instance extending from the B terminal of battery 22, over front contact 30 of relay RGR, front contact 38 of relay LGR, and to the winding of relay 9NWR in the event the polar armature 39 of relay 9WR occupies its normal position; and to the winding of relay 9RWR in the event the polar armature 39 occupies its reverse position as will be readily understood by an inspection of Fig. 2. Selecting relay 9NWR completes a circuit for energizing the relay 9WR in its reverse position to move the switch 9 to its reverse position, and the selecting of relay 9RWR completes a circuit for energizing relay 9WR in its normal position to bring about a normal operation of switch 9. It follows that energizing the dispatcher controlled relay LGR for an interval selects the group of control relays for the switch mechanism 6M and these relays function to bring about an operation of switch 6; energizing the dispatcher controlled relay RGR for an interval selects the group of control relays for the switch mechanism 7M and these relays function to bring about an operation of the switch 7; and energizing both relays LGR and RGR for an interval selects the group of control relays for mechanism 9M and these relays function to bring about an operation of the switch 9.

Operatively connected with the derailing switch 6 is a set of circuit controlling contacts 25, 26, 27 and 28. These contacts control a polarized switch controlled relay 6KR, the circuit including a polar armature 29 of the switch controlling relay 6WR. In the normal position of the switch 6, current is supplied from the B terminal of battery 22 over contact 28, normal position of polar armature 29, winding of relay 6KR and contact 27 to the opposite terminal N of battery 22. When the switch 6 is reversed, contacts 25, 26, 27 and 28 are reversed; and the circuit for the relay 6KR extends from the B terminal of battery 22 over contact 25, winding of relay 6KR, reverse position of polar armature 29, and contact 26 to the opposite terminal N of battery 22. 150

Thus, the switch controlled relay 6KR is energized with one polarity of current when the switch is normal, and is energized with current of the reverse polarity when the switch 6 is set in its reverse position, agreement being required between the position of the polar armature 29 of the switch controlling relay 6WR and the contacts operated by the switch 6. A similar set of contacts 33, 34, 35 and 36 is operatively connected with the derailing switch 7, and this set of contacts together with a polar armature 37 of the switch controlling relay 7WR govern an associated switch controlled relay 7KR in the same manner as just described for relay 6KR. That is to say, with switch 7 set in its normal position, and polar armature 37 in its normal position, relay 7KR is energized with current of one polarity; and when the switch 7 is set in its reverse position and polar armature 37 is reversed, the relay 7KR is energized with current of the reverse polarity. A set of contacts 40, 41, 42 and 43 is operatively connected with the switch 9; and this set of contacts together with the polar armature 44 of relay 9WR govern the operation of a switch controlled relay 9KR as will be readily understood by an inspection of Fig. 2.

The railway track X includes a track section 6T, and the railway track Y includes a track section 8T. Track section 6T and the track section 8T are each provided with the usual track circuit, which includes a battery 5 connected across the rails at one end of the section and a track relay R with a prefix corresponding to the track section, connected across the rails at the opposite end of the section.

Referring now to Fig. 1, the office station is provided with three spring return push buttons designated by the reference characters 6PB, 7PB and 9PB, and these push buttons govern the operation of switches 6, 7 and 9, respectively. Associated with each push button are two control relays PBR and PBS, and two indicating relays NKP and RKP, a prefix corresponding to the associated push button being added in each case. The control relays PBR and PBS are each slow releasing in character, and the indicating relays NKP and RKP are each provided with two windings as will shortly be described.

Each push button controls its associated control relays in the following manner. Depressing push button 6PB, for example, completes an energizing circuit for both its associated control relays 6PBR and 6PBS. The circuit for relay 6PBR extends from the B terminal of a battery 45, through back contacts 46 and 47 of relays 6OSR and 8OSR, respectively, and which relays will be later described, wire 53, back contacts 50 and 51 of relays 9PBS and 7PBS, respectively, contact 48 of push button 6PB, winding of relay 6PBR, and to a center terminal C of the battery 45. The circuit for the relay 6PBS is the same as just traced up to the back contact 51 of relay 7PBS, and thence over contact 49 of push button 6PB, winding of relay 6PBS, and to the center C terminal of battery 45. Thus, depressing the push button 6PB causes both the control relays 6PBR and 6PBS to become energized, providing the stick relays 7PBS and 9PBS for the push buttons 7PB and 9PB, respectively, are deenergized, and providing the two relays 6OSR and 8OSR are also deenergized. Relay 6PBS is provided with a stick circuit for retaining that relay energized after the push button 6PB has been restored to its normal position. Assuming the two indicating relays 6NKP and 6RKP to both be deenergized

in a manner to later appear, the stick circuit for relay 6PBS can be traced from the B terminal of battery 45, back contacts 54 and 55 of relays 6NKP and 6RKP, respectively, front contact 56, winding of relay 6PBS, and to the C terminal of battery 45. It follows that when push button 6PB is released after it has once been depressed, current is cut off from the control relay 6PBR, and that relay releases at the end of a slow release period, but the stick relay 6PBS will remain energized over its stick circuit as long as the associated indicating relays are both deenergized.

Referring now to push button 7PB, this push button controls the energizing of its control relays 7PBR and 7PBS in a manner similar to that just described for the push button 6PB. The energizing circuit for relay 7PBR extends from the B terminal of battery 45 over back contacts 46 and 47, wire 52, back contacts 58 and 59 of the opposing stick relays 6PBS and 9PBS, respectively, contact 60 of push button 7PB, winding of relay 7PBR, and to the center C terminal of battery 45; while the circuit for the relay 7PBS is the same as that just traced up to the back contact 59 of relay 9PBS, and thence through contact 57 of push button 7PB, winding of relay 7PBS, and to the center C terminal of battery 45. Although the control relay 7PBR has its circuit opened when the push button 7PB is restored to its normal position and hence releases at the end of its slow release period; the stick relay 7PBS is retained energized over a stick circuit easily traced, and which includes the back contacts 64 and 65 of the associated indicating relays 7NKP and 7RKP, respectively, and its own front contact 63. It is to be noted that operating the push button 7PB is ineffective to energize its control relays unless the stick relays 6PBS and 9PBS for the other two push buttons 6PB and 9PB, and the relays 6OSR and 8OSR are all deenergized.

In like manner, the push button 9PB controls the energizing of its control relays 9PBR and 9PBS, the circuit branching from the wire 52 along wire 71, back contacts 68 and 69 of the opposing stick relays 7PBS and 6PBS, respectively, contact 70 of push button 9PB, winding of relay 9PBR, and to the C terminal of battery 45; and through the contact 66 of push button 9PB, winding of relay 9PBS, and to the C terminal of battery 45. Returning the push button 9PB to its normal position will at once cut off current from the control relay 9PBR, and that relay releases at the end of the slow release period, but the stick relay 9PBS will be now retained energized by a stick circuit which includes the back contacts 73 and 74 of the associated indicating relays 9NKP and 9RKP, respectively, and its own front contact 72. Again, it is to be noted that the push button 9PB is ineffective to pick up its control relays unless the stick relays 7PBS and 6PBS of the other two push buttons 6PB and 7PB, and relays 6OSR and 8OSR are all deenergized. It is clear from the foregoing that operating any one of the push buttons 6PB, 7PB or 9PB results in the energization of the associated control relays, and that the associated stick relay is retained energized after the push button has been restored to its normal position as long as the associated indicating relays are deenergized. The energized condition of the stick relay renders each of the remaining push buttons ineffective to pick up its associated control relays.

The office station of Fig. 1 is connected with the field station of Fig. 2 by a pair of line wires

designated by the reference characters L and Com, the line wire Com being connected directly to the center C terminal of both the batteries 45 and 22; and the line wire L being connected to 5 either the B or the N terminal of these two batteries 45 and 22 in accordance with the condition of the apparatus at the office station and at the field station as will now be described. Depressing push button 6PB and the subsequent 10 energization of the control relays 6PBR and 6PBS connects the B terminal of battery 45 with the line wire L over front contact 75 of relay 6PBR, back contacts 76 and 77 of the opposing stick relays 7PBS and 9PBS, respectively, and front 15 contact 78 of the associated stick relay 6PBS. In the event the push button 7PB is operated and its control relays 7PBR and 7PBS are subsequently energized, the N terminal of battery 45 is connected with the line wire L over front contact 20 79 of relay 7PBR, back contacts 80 and 81 of the opposing stick relays 6PBS and 9PBS, respectively, and the front contact 82 of the associated stick relay 7PBS. In case the push button 9PB is operated and its associated control 25 relays 9PBR and 9PBS are subsequently energized, two relays 83 and 84 are operated to alternately connect the B and the N terminals of battery 45 to the line wire L. Relay 9PBR when picked up closes a front contact 85, and current 30 flows from the B terminal of battery 45 over front contact 85, back contact 86 of relay 84, winding of relay 83, and to the terminal C of battery 45. Relay 83 on picking up, closes its front contact 87 and current is supplied to the winding of relay 35 84 by a simple circuit that includes the front contacts 85 and 87. Relay 84 in picking up opens the back contact 86 removing current from the relay 83, and that relay releases to in turn open its front contact 87 removing current from 40 the relay 84. These two relays 83 and 84 thus alternately pick up and release as long as the front contact 85 of the relay 9PBR remains closed, each relay controlling the connection to the other. During each interval that relay 83 is 45 picked up, the N terminal of battery 45 is connected with the line wire L over front contact 88, front contact 89 of relay 9PBR, back contacts 90 and 91 of the opposing stick relays 6PBS and 7PBS, respectively, and the front contact 92 of 50 the associated stick relay 9PBS. During each interval the relay 83 is deenergized, the B terminal of battery 45 is connected with the line wire L over front contact 85, back contact 93, and thence the same as previously traced. 55 It is clear from the foregoing description that operating the push button 6PB causes an impulse of current of positive polarity to be supplied to the line circuit the duration of which is equal to the interval the push button 6PB is held down plus the slow release period of the relay 6PBR. When the push button 7PB is operated, an impulse of current of negative polarity is supplied to the line circuit, the duration of which is equal to the interval the push button 7PB is 65 held down plus the slow release period of the relay 7PBR. Operating the push button 9PB causes impulses of current alternately positive and negative in polarity, to be supplied to the line circuit during the slow release period of the 70 control relay 9PBR. In each instance, the associated stick relay renders each of the other two push buttons ineffective to operate its control relays.

Referring again to Fig. 2, the dispatcher controlled relays LGR and RGR each have one terminal of its winding connected directly to the common line wire Com at the C terminal of battery 22. The opposite terminal of the winding of relay LGR is connected with the line wire L through a circuit network which can be traced from the line wire L over front contact 20 of the track relay 6TR, front contact 94 of the track relay 8TR, back contacts 95, 96 and 97 of the switch controlling relays 6WR, 7WR and 9WR, respectively, wire 98, and a half-wave rectifier 99. 80 The opposite terminal of the winding of the relay RGR is connected to the line wire L through this same circuit network up to wire 98 and thence through a half-wave rectifier 100. The rectifiers 99 and 100 are arranged with their low resistance or forward direction reversed to each other and are so positioned that when current of positive polarity is applied to the line circuit, the relay LGR is energized, and when the current supplied to the line circuit is of negative polarity, the relay RGR is energized. When impulses of current alternate in polarity flow in the line circuit then both relays LGR and RGR are energized, half-wave rectifiers 101 and 102 being connected 85 across the windings of the relays LGR and RGR, 100 respectively, to make these relays slightly slow releasing. Consequently, when push button 6PB is operated and an impulse of current of positive polarity is supplied to the line circuit, the relay LGR at the field station is selected and the control relays 6WR, 6RWR and 6NWR are operated to effect an operation of switch 6. Depressing the push button 7PB and the consequent supplying of an impulse of current of negative polarity to the line circuit, selects the relay RGR at the 105 field station and the control relays 7WR, 7RWR and 7NWR are operated to effect a movement of the switch 7. Actuating the push button 9PB results in impulses of current alternate in polarity being supplied to the line circuit and both relays 110 LGR and RGR are picked up to operate the control relays for the switch mechanism 9M to bring about an operation of the switch 9. In each instance the picking up of the associated stick relay as a push button is operated renders the 115 other two push buttons ineffective.

The manner of indicating the position of switches 6, 7 and 9 will now be taken up. As previously pointed out, each push button is provided with a normal indicating relay NKP and a reverse indicating relay RKP. These indicating relays are of the double winding type, one winding being included in a pick-up circuit for receiving an impulse from the line circuit, and the second winding being included in a local stick circuit for 120 retaining the relay energized after an indication impulse has been received. Referring to the relays 6NKP and 6RKP for the push button 6PB, these relays each have one terminal of their pick-up or top winding connected directly to the common line wire at the C terminal of the battery 125 45. The other terminal of the top winding of relay 6NKP is connected with the line wire L over a loop circuit including a half-wave rectifier 103, back contact 104 of relay 6PBR, back contacts 76 130 and 77 of the stick relays 7PBS and 9PBS, respectively, and front contact 78 of the stick relay 6PBS. The other terminal of the top winding of relay 6RKP is connected with the line wire L over a loop circuit including a half-wave rectifier 105, 135 back contact 104, and thence over the same circuit just traced for relay 6NKP. The rectifier 103 is so positioned as to pass current flowing from the line wire L toward the common line wire Com, and to substantially block the flow of 140 145 150

current in the opposite direction, and the rectifier 105 is so positioned as to pass current flowing from the common line wire *Com* toward the line wire *L* and to substantially block the flow of current in the opposite direction. It follows that at such time as the stick relay 6PBS is picked up to close its front contact 78 and the control relay 6PBR is down to close its back contact 104, an impulse of current of one polarity will pass through the rectifier 103 to energize the relay 6NKP, and an impulse of current of the opposite polarity will pass through the rectifier 105 to energize the relay 6RKP. In other words, as soon as the control relay 6PBR is released to terminate an outgoing control impulse, the two loop circuits including the indicating relays 6NKP and 6RKP, respectively, are connected with the line circuit, one loop circuit being so arranged as to respond to current of one polarity and the other loop circuit being so arranged as to respond to current of the opposite polarity. Once the relay 6NKP is picked up, it will be retained energized by virtue of a stick circuit extending from the *B* terminal of the battery 45 over the back contact 106 of relay 6PBR, its own front contact 107, and the lower or stick winding to the *C* terminal of battery 45. In like manner, the relay 6RKP once picked up, it will be retained energized by a stick circuit extending from the *B* terminal of battery 45 over back contact 106, its own front contact 108, and its lower winding to the *C* terminal of the battery 45. Relay 6NKP controls at its front contact 109 a simple circuit for a normal indicating device 6N, and the relay 6RKP controls at its front contact 110 a simple circuit for a reverse indicating device 6R. Half-wave rectifiers 111 and 112 may be connected across the top windings of relays 6NKP and 6RKP, respectively, to provide these relays with a slow releasing characteristic.

In a similar manner, the indicating relays 7NKP and 7RKP for the push button 7PB each have one terminal of their top winding connected directly with the common line wire *Com* at the terminal *C*; the other terminal of the top winding of relay 7NKP being connected with the line wire *L* over a loop circuit including a half-wave rectifier 113, back contact 114 of relay 7PBR, back contacts 80 and 81 of the stick relays 6PBS and 9PBS, respectively, and the front contact 82 of the stick relay 7PBS. The other terminal of the top winding of relay 7RKP is connected with the line wire *L* over a loop circuit including a half-wave rectifier 115, back contact 114, and thence by the circuit just traced for the relay 7NKP. Rectifiers 113 and 115 have their forward directions reverse to each other and are so arranged that an impulse flowing from the common line wire toward the line wire *L* will energize the relay 7RKP, and an impulse flowing from the line wire *L* toward the common line wire *Com*, will energize the relay 7NKP. Again, it is to be noted that after the control relay 7PBR associated with push button 7PB releases to terminate an outgoing control impulse, the associated stick relay 7PBS is retained energized to connect the two indicating loop circuits for the push button 7PB with the line circuit. Relay 7NKP once picked up, it will be retained energized by a stick circuit that includes the back contact 116 of the control relay 7PBR, its own front contact 117, and its lower winding. Relay 7RKP once picked up it will be retained energized by a stick circuit that includes the back contact 116, its own front contact 118 and its lower winding. Relays 7NKP and 7RKP control at their respective front contacts 119 and 120, normal and reverse indicating devices 7N and 7R.

Again, the indicating relays 9NKP and 9RKP for the push button 9PB each have one terminal of their top winding connected with the common line wire at the terminal *C*; the opposite terminal of the top winding of relay 9NKP being connected with the line wire *L* over a loop circuit that includes a half-wave rectifier 121, back contact 122 of the associated control relay 9PBR, back contacts 90 and 91 of the stick relays 6PBS and 7PBS, respectively, and the front contact 92 of the associated stick relay 9PBS; and the other terminal of the top winding of relay 9RKP being connected with the line wire *L* over a loop circuit that includes a half-wave rectifier 123 and the circuit just traced above. Consequently, as soon as the relay 9PBR releases to terminate an outgoing control impulse, the stick relay 9PBS connects the two associated loop circuits with the line circuit, the rectifiers 121 and 123 being so arranged that one loop circuit will pass current of one polarity and the other loop circuit will pass current of the opposite polarity. A stick circuit for the relay 9NKP is easily traced from the *B* terminal of battery 45 over back contact 124 of relay 9PBR, front contact 125, and lower winding of that relay; and a stick circuit for the relay 9RKP includes back contact 124, its own front contact 126, and its lower winding. These two relays 9NKP and 9RKP control at their respective front contacts 127 and 128, the normal and reverse indicating devices 9N and 9R. It is clear from the foregoing description of the indicating loop circuits associated with each push button that when a push button is operated to initiate a control impulse, the associated stick relay is retained energized to connect the associated loop circuits with the line circuit after the control impulse has been terminated, one loop circuit being arranged to respond to current of one polarity and the other loop circuit being arranged to respond to current of the opposite polarity. When an indicating relay has once been selected by an indicating impulse, that relay is retained energized by a local stick circuit to continuously energize a corresponding indicating device.

Referring now to Fig. 2, a current impulse for indicating the position of a switch is governed jointly by the associated switch controlled relay KR and the associated switch controlling relay WR. In my copending application Serial No. 631,041, it is described in detail how at the completion of a movement of a railway switch, the switch controlled relay KR is energized in a corresponding position, and as the KR relay is picked up, current is removed from the switch controlling relay WR and the winding of that relay is short-circuited to give that relay a slow release action. For example, movement of the switch 6 causes the controlled relay 6KR to be energized in the corresponding position and the controlling relay 6WR to be deenergized and released with a slow release action. During the slow release period of the relay 6WR, an indicating impulse is supplied to the line circuit, the polarity of which is determined by the position of the 6KR relay. With the switch 6 in its reverse position and the 6KR relay in its reverse energized position, a connection is completed from the *N* terminal of field battery 22 over the polar armature 129 of relay 6KR, front contact 130 of relay 6KR, front contact 131 of relay 6WR, and the front contacts 94 and 20 of the two track 150

relays 8TR and 6TR, respectively, and to the line wire L. In the event the switch 6 is moved to its normal position then this connection extends from the B terminal of battery 22 over 5 polar armature 129, front contacts 130, 131, 94 and 20 to the line wire L. In other words, the reverse indicating impulse for the switch 6 will flow from the battery 22 at the field station over the common line wire Com to the office station 10 through a corresponding loop circuit, and thence back over the line wire L to the N terminal of battery 22, and the normal indicating impulse for switch 6 will flow from the B terminal of battery 22 over the line wire L to the office station 15 through a corresponding loop circuit, and back over the common line wire Com to the C terminal of battery 22. Operating switch 7 to its reverse position and the subsequent energization of the 7KR relay in its reverse position completes a connection from the N terminal of battery 22 over 20 the reverse position of polar armature 132 of relay 7KR, front contact 133, front contact 134 of the switch controlling relay 7WR, back contact 95, and front contacts 94 and 20 to the line 25 wire L. Moving the switch 7 to its normal position and the subsequent energization of the 7KR relay in its normal position completes a connection from the B terminal of battery 22 to the line wire L over the same circuit just traced above. 30 In like manner, the polar armature 135 of the switch controlled relay 9KR for switch 9, its front contact 136, and the front contact 137 of the switch controlling relay 9WR function to complete a connection from either the B or N terminal of battery 22 to the line wire L immediately following a movement of the switch 9. It is clear, therefore, that an impulse of current of negative polarity is supplied to the line circuit 35 subsequent to an operation of switch 6, 7 or 9 to the reverse position, and an impulse of current of positive polarity is supplied to the line circuit subsequent to an operation of switch 6, 7 or 9 to the normal position, the duration of each impulse being equal to the release period of the associated switch controlling relay. 40

In describing the operation of the system as a whole, I shall first assume that the switches 6, 7 and 9, and their respective control relays occupy the normal position, that is, the position illustrated in the drawings. I shall further assume that the track circuits for the track sections 6T and 8T are both unoccupied, and also that the normal indicating relay NKP for each push button is energized. I shall next assume that the dispatcher desires to move the switch 6 and hence depress the push button 6PB for an interval and then release it. When the push button 6PB is depressed, the two control relays 6PBR and 6PBS are picked up over their energizing circuits. Relay 6PBR in picking up opens the back contact 106 to deenergize the indicating relay 6NKP and that relay releases to extinguish the indicating device 6N, and to complete the stick circuit for the relay 6PBS at the back contact 54. As the push button 6PB is restored to its normal position, current is removed from the relay 6PBR and that relay releases at the end of its slow release period, but the stick relay 6PBS remains energized over its stick circuit. During the interval 65 that relays 6PBR and 6PBS are both up, a control impulse of current of positive polarity is supplied to the line circuit and the relay LGR of the field station is energized. Relay LGR, in turn, completes the circuit to the controlling relays for the switch mechanism 6M, and these 70

75

relays then function to bring about the operation of the switch 6 to its reverse position. When the relay 6PBR is released, the loop circuits for the push button 6PB are connected to the line wires, the connection being completed at the back contact 104. As soon as the switch 6 is fully reversed, and the 6KR relay is energized in its reverse position; an indicating impulse of current of negative polarity is supplied to the line wires during the release period of relay 6WR, and this indicating impulse is passed by the rectifier 105 and the indicating relay 6RKP is energized and then retained energized by its local stick circuit. Relay 6RKP upon picking up, causes the display of the reverse indicating device 6R, and opens the stick circuit to the relay 6PBS at the back contact 55, and that relay is deenergized. It is to be noted that the stick relay 6PBS is retained picked up until the indication is completed, and that as long as the relay 6PBS is picked up the back contacts 58 and 80 are open and the push button 7PB is rendered ineffective; and, also, the back contacts 69 and 90 are open to render the push button 9PB ineffective. In other words, operating the push button 6PB locks out the remaining two push buttons until the operation initiated by the push button 6PB has been fully completed and indicated. 90

I shall now assume that the dispatcher desires to return the switch 6 to its normal position. 105 By operating the push button 6PB the second time, the relays 6PBR and 6PBS are picked up over their energizing circuit the same as before, and the indicating relay 6RKP is released to extinguish the indicator 6R, and to complete the 110 stick circuit for relay 6PBS. The control impulse supplied to the line wires again selects the relay LGR, but this time the relay 6RWR of the control group is selected as the polar armature 21 is in the reverse position and hence the switch 6 115 is operated to its normal position. When the relay 6KR is picked up in its normal position at the completion of the movement of switch 6, an indicating impulse of current of positive polarity is supplied to the line wires and this impulse 120 will pass through the rectifier 103 to energize the normal indicating relay 6NKP, and that relay in turn establishes the normal indicator 6N and opens the stick circuit for relay 6PBS at the back contact 54. Again it is to be noted that the stick 125 relay 6PBS is retained energized until the operation is fully completed and that as long as that relay is energized, the push buttons 7PB and 9PB are rendered ineffective. 130

To bring about an operation of the switch 7, the dispatcher will depress the push button 7PB for a brief interval and then release it. The control relays 7PBR and 7PBS will be picked up over their energizing circuits to deenergize the associated indicating relays, and to supply a control impulse to the line wires. The control impulse this time will be current of negative polarity and the relay RGR will be selected which in turn, completes the circuit to the control relays for the switch mechanism 7M. Relay 7WR 140 of this control group being in its normal position, the switch 7 will be moved to its reverse position, after which the 7KR relay will be energized in its reverse position and an indicating impulse of current of negative polarity will be 145 supplied to the line wires. Relay 7PBR having released in the meantime, this indicating impulse will be passed by the rectifier 115 and indicating relay 7RKP energized to establish the reverse indicating device 7R, and to deenergize the 150

stick relay 7PBS. It will be noted that the stick relay 7PBS when energized renders the push button 6PB ineffective by opening of the back contacts 51 and 76, and renders the push button 5 9PB ineffective by opening the back contacts 68 and 91. Operating the push button 7PB the second time will cause the relays 7PBR and 7PBS to be energized in the manner described for the first operation of push button 7PB; and a control impulse will be supplied to the line wires to select the relay RGR, and in turn, select the control relays for mechanism 7M. Polar armature 32 now being in its reverse position, relay 7WR will be energized in its normal position and the 10 switch 7 will be operated to its normal position and an indicating impulse of current of positive polarity will be supplied to the line wires which impulse will select the indicating relay 7NKP to establish the normal indicator 7N, and to de- 15 energize the stick relay 7PBS.

To effect a movement of the switch 9, the dispatcher will depress the push button 9PB to energize the control relays 9PBR and 9PBS. Relay 9PBR when energized not only opens the 20 stick circuit for the associated indicating relay at the back contact 124, but also completes the circuit at the front contact 85 from operating the two relays 83 and 84 which, in turn will cause control impulses alternate in polarity to be supplied to the line wires as long as the relay 9PBR remains picked up. The relays 83 and 84 are so proportioned as to operate faster than the relays LGR and RGR, and consequently, the control impulses alternate in polarity will cause the 25 two relays LGR and RGR to be simultaneously energized. With both relays LGR and RGR picked up at the same time, the control relays for the switch mechanism 9M will be selected and the switch 9 will be operated. In the event 30 the switch 9 is moved to its reverse position, the indicating impulse will be current of negative polarity to select the indicating relay 9RKP to establish the reverse indicator 9R. In the event the switch 9 is moved to its normal position, the 35 indicating impulse will be current of positive polarity, and the relay 9NKP will be selected to establish the normal indicator 9N. Again it will be noted that as long as the stick relay 9PBS is picked up, the push button 6PB will be rendered 40 ineffective by the opening of the back contacts 50 and 77; and the push button 7PB will be rendered ineffective by the opening of the back contacts 59 and 81.

It is clear from the foregoing description of the 45 operation of the switches 6, 7 and 9 that the control impulses are supplied to the line circuit for only a brief interval; and that the return indicating impulses also last only for a brief interval, the line circuit being idle the remaining 50 portion of the time. This being true, I propose to utilize the line circuit for OS-ing the occupancy of track sections in the vicinity of the switches. Assuming a train enters the track section 6T and shunts the track relay 6TR to 55 deenergize that relay. When relay 6TR releases, the closing of its back contact 138 completes a connection from the B terminal of the battery 22 to the line wire L and current flows from the B terminal of battery 22 through back contact 60 138, line wire L, back contacts 139, 140 and 141 of the stick relays 9BPS, 7BPS and 6BPS, respectively, half-wave rectifier 143, winding of the relay 6OSR to the C battery terminal at the office station, and thence over the common line 65 wire Com to the C battery terminal at the field

station. Relay 6OSR is now picked up and completes a simple circuit at its front contact 144 to an indicating light 6TL. It follows that the light 6TL is displayed to indicate the occupancy of the track section 6T as long as the track relay 6TR remains down. In the event the train enters the track section 8T and shunts the track relay 8TR, the closing of its back contact 145 completes a connection from the N terminal of battery 22 to the line wire L, and current flows from the C battery terminal at the field station over the common line wire Com to the C battery terminal at the office station, through winding of relay 8OSR, rectifier 147, back contacts 141, 140 and 139, and line wire L to the N terminal of battery 22 through the back contact 145. Relay 8OSR in picking up completes at its front contact 148, a simple circuit to the light 8TL, and hence this light 8TL is displayed to indicate the occupancy of the track section 8T. It is to be noted that as long as either relay 6OSR or 8OSR is energized and either back contact 46 or 47 open the push buttons are ineffective to initiate a control impulse.

A control system such as here disclosed provides for governing the operation of at least three railway switches over a single pair of line wires by simple and reliable apparatus; the line circuit at the same time being available for OS-ing track sections in the vicinity of the switches.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A control system for railway switches including, a plurality of railway switches at one point, a manually operated circuit controller for each railway switch and located at a second point, a slow release control relay and a stick control relay for each circuit controller and both normally deenergized, means effective upon operating a circuit controller to an active position to energize its control relays, a stick circuit for each stick relay for retaining the relay energized after the circuit controller is restored to an inactive position, means controlled by each stick relay 115 when energized for rendering each of the remaining circuit controllers ineffective to energize its control relays, control means effective to supply a control impulse during the release period of the slow release relay for establishing an operation 120 of the corresponding switch, an indication means for each circuit controller, an indication means for each switch adapted to supply an indicating impulse in response to each operation of the switch for influencing the corresponding indication means, and means governed by each indication means for opening the stick circuit of the associated stick relay in response to an indicating impulse and thereby restore the control of each of the circuit controllers over its control 125 relays.

2. A control system for railway switches including, a plurality of railway switches at one point, a manually operable circuit controller for each railway switch and located at a second point, a pair of line wires extending between said two points, a control means and a normally deenergized stick relay for each circuit controller, means effective upon operating a circuit controller to an active position for energizing its stick relay and 145

- for rendering its control means active to supply a control impulse to the line wires for effecting an operation of the corresponding switch, a stick circuit for each stick relay for retaining the relay energized after the circuit controller is restored to an inactive position, means controlled by each stick relay when energized for rendering each of the remaining circuit controllers ineffective to govern its control means, an indication means for 5 each circuit controller governed by the control means and arranged to be connected with the line wires at the termination of a control impulse, an indication means for each switch adapted to supply to the line wires an indicating impulse in response to an operation of the switch for influencing the corresponding indication means, and means governed by each indication means for opening the stick circuit of the associated stick relay in response to an indicating impulse where- 10 by the control of each of the other circuit controllers over its control means is restored.
3. A control system for railway switches including, a plurality of railway switches located at one point, a push button for each of said railway switches and located at a second point, a pair of line wires extending between said two points, a slow release control relay and a stick control relay for each push button and both normally deenergized, means effective upon operation of a push 15 button for energizing its control relays, a stick circuit for each stick relay for retaining the relay energized after the push button is released, means controlled by each stick relay when energized for rendering each of the other push buttons ineffective to energize its control relays, control 20 means effective to supply a control impulse during the release period of the slow release relay to the line wires for effecting an operation of the corresponding switch, an indication circuit means 25 for each push button and connected with said line wires when its stick relay is energized, an indication means for each switch adapted to supply an indicating impulse to the line wires in response to each operation of the switch for influencing the 30 indication circuit means, and means governed by each indication circuit means for opening the stick circuit of the associated stick relay in response to an indicating impulse.
4. A control system for railway switches including, a plurality of railway switches located at one point, a push button for each of said switches and located at a second point, a pair of line wires extending between said two points, a control 35 means for each push button rendered active in response to an operation of the push button to supply a control impulse to the line wires for effecting an operation of the corresponding switch, a relay for each push button adapted to be energized in response to an operation of the push button, a stick circuit for each relay for retaining the relay energized after the push button is released, means controlled by each relay when energized for rendering each of the remaining push buttons ineffective to govern its 40 control means, an indication means for each push button governed by the control means and arranged to be connected with the line wires at the termination of a control impulse, an indication means for each switch adapted to supply to the line wires an indicating impulse in response to an operation of the switch for influencing the corresponding indication means, and means governed by each indication means for opening the stick circuit of the associated relay in response to 45 an indicating impulse.
5. A control system for railway switches including, a plurality of railway switches located at one point, a push button for each of said switches and located at a second point, a pair of line wires extending between said two points, a control 50 means for each push button rendered active in response to an operation of the push button to supply a control impulse to the line wires for effecting an operation of the corresponding switch, a relay for each push button adapted to be energized in response to an operation of the push button, a stick circuit for each relay for retaining the relay energized after the push button is released, means controlled by each relay when energized for rendering each of the remaining push buttons ineffective to govern its control means, an indication means for each push button controlled jointly by the control means and the relay and arranged to be connected with the line wires at the termination of a control impulse only if said relay is energized, an indication means for each switch adapted to supply to the line wires an indicating impulse in response to an operation of the switch for influencing the indication means, and means governed by each indication means for opening the stick circuit of the associated relay in response to an indicating impulse.
6. A control system for railway switches including, a plurality of railway switches located at one point, a push button for each of said railway switches and located at a second point, a pair of line wires extending between said two points, a pair of loop circuits for each push button each adapted to pass current in one direction only and arranged to receive current from said line wires but normally disconnected, control means effective upon operation of a push button to supply a control impulse of a given duration to said line wires for effecting operation of the corresponding switch, means governed by said control means to automatically connect the loop circuits of the operated push button with said line wires at the expiration of the control impulse, indication means for each switch effective upon operation of the switch to supply to said line wires an impulse of current of positive or negative polarity according to the position of the switch for influencing the loop circuits of the associated push button, and a normal and a reverse indication means selectively governed by the loop circuits.
7. A control system for railway switches including, a plurality of railway switches located at one point, a push button for each of said railway switches and located at a second point, a pair of line wires extending between said two points, a pair of loop circuits for each push button each adapted to pass current in one direction only and arranged to receive current from said line wires but normally disconnected, a slow release control relay and a stick control relay for each push button and both normally deenergized, means effective upon operation of a push button to energize its two control relays, control means governed by said relays for supplying to the line wires a control impulse during the release period of the slow release relay for effecting an operation of the corresponding switch, means governed by said two relays for connecting the associated loop circuits with the line wires at the expiration of said control impulse, indication means for each switch effective upon operation of the switch to supply to said line wires for a given interval an impulse of current of positive or negative polarity according to the position of the switch for influencing the loop circuits of the associated push button, a

normal and a reverse indicating relay for each push button and selectively controlled by its loop circuits, and means governed by said indicating relays for indicating the position of the switch and for controlling the stick circuit of the associated stick relay.

8. A control system for railway switches including, a plurality of railway switches located at one point, a push button for each of said rail-way switches and located at a second point, a pair of line wires extending between said two points, a pair of loop circuits for each push button each adapted to pass current in one direction only and arranged to receive current from said line wires but normally disconnected, a slow release control relay and a stick control relay for each push button and both normally deenergized, means effective upon operation of a push button to energize its two control relays, a stick circuit for retaining the stick relay energized after the push button is released, means governed by each stick relay when energized for rendering each of the remaining push buttons ineffective to energize its control relays, a control means effective to supply to the line wires a control impulse during the release period of the slow release relay for effecting an operation of the corresponding switch, circuit means completed with the slow release relay down and the stick relay picked up 25 for connecting the associated loop circuits with the line wires, indication means for each switch effective upon operation of the switch to supply to the line wires an impulse of current of positive or negative polarity according to the position of the switch for influencing the loop circuits of the associated push button, a normal and a reverse indicating relay for each push button selectively controlled by its loop circuits, a normal and a reverse indicator selectively governed by the indicating relay, and means governed by said indicating relays for controlling the stick circuit of the associated stick relay whereby each of the remaining push buttons is again rendered effective to energize its control relays at the completion 30 of the indication.
- 45 9. A control system for railway switches including, two switch controlling means located at one point and each adapted when energized to govern the operation of a corresponding switch, a push button for each switch and located at a second point, a pair of line wires extending between said one point and said second point, a pair of loop circuits at said one point normally connected with the line wires and each adapted to pass current in one direction only, means controlled by said loop circuits for selectively energizing the switch controlling means, a pair of loop circuits for each push button normally disconnected from said line wires and each adapted to 40 pass current in one direction only; control means effective upon operation of a first push button to supply a control impulse of current of positive polarity to said line wires for influencing the corresponding loop circuit at said one point to cause operation of the corresponding switch, and effective upon operation of the second push button to supply a control impulse of current of negative polarity for influencing the other loop circuit at said one point to cause operation of the other switch; means governed by said control means to connect the loop circuits for the operated push button with the line wires, and means governed by each switch when operated to supply to said line wires an impulse of current of either positive 55 or negative polarity according to the position of

said switch for influencing the corresponding loop circuit of the operated push button for indicating the position of said switch.

10. A control system for railway switches including, three switch controlling devices located at one point and each adapted to govern the operation of a corresponding switch and to at times supply an indicating current, three manually operated levers located at a second point, an indication means for each lever, a single line circuit connecting said two points, a pair of loop circuits connected with the line circuit at said one point and each including a relay and a half-wave rectifier with the rectifiers arranged in reverse directions, means effective to control one of the switch controlling devices when one of said relays is energized, to control a second one of the switch controlling devices when the other of said relays is energized and to control the third switch controlling devices when both relays are simultaneously energized; a current source rendered effective to supply current of one polarity to the line circuit when one of said levers is operated, to supply current of opposite polarity when a second one of said levers is operated and to supply impulses of current alternate in polarity when the third lever is operated, and means governed by each lever when operated to render the other levers ineffective to govern said current source and to automatically connect the corresponding 100 indication means with said line circuit to receive the indicating current from the selected switch controlling device.
11. A control system for railway switches including, three switch controlling devices located at one point and each adapted to govern the operation of a corresponding switch and to at times supply an indicating current, three manually operated levers located at a second point, an indication means for each lever, a single line circuit connecting said two points, a pair of loop circuits connected with the line circuit at said one point and each including a relay and a half-wave rectifier with the rectifiers arranged in reverse directions; means effective to control one of the switch controlling devices when one of said relays is energized, to control a second one of the switch controlling devices when the other of said relays is energized and to control the third switch controlling devices when both relays are simultaneously energized; a current source rendered effective to supply an impulse of current of one polarity to the line circuit when one of said levers is operated, to supply an impulse of current of opposite polarity when a second one of said levers is operated and to supply impulses of current alternate in polarity when the third lever is operated; means governed by each lever when operated to render the other levers ineffective to govern said current source and to automatically connect the corresponding 110 indication means with said line circuit to receive the indicating current from the selected switch controlling device.
12. A control system for railway switches including, two switch operating devices located at one point and each adapted to govern the operation of a corresponding switch and to supply at times an indicating current impulse in accordance with the position of the switch, two manually operated levers located at a second point, an indication means for each lever, a pair 115

- 125 130 135 140 145 150
13. A control system for railway switches including, two switch operating devices located at one point and each adapted to govern the operation of a corresponding switch and to supply at times an indicating current impulse in accordance with the position of the switch, two manually operated levers located at a second point, an indication means for each lever, a pair

of line wires extending between the two points, a pair of loop circuits connected with said line wires at said one point and each including a relay and a half-wave rectifier with the rectifiers arranged reverse to each other, means effective to control one of the switch operating devices when one of the relays is energized and to control the other switch operating device when the other relay is energized, means effective to supply a control impulse of current of positive polarity to the line wires when one of the levers is operated and to supply a control impulse of current of negative polarity when the second lever is operated to selectively energize the relays of said loop circuits, means governed by each lever when operated to render the other lever ineffective and to automatically connect the corresponding indication means with the line wires at the end of the control impulse to receive the indicating current impulse of the selected switch controlling device, and means governed by each indication means to indicate the position of the switch and to restore the other lever to its effective condition.

13. A control system for railway switches including, a railway switch at one point, a manually operated circuit controller normally occupying an inactive position and located at a second point, a pair of line wires extending between the two points, circuit means connected with the line wires at said one point and responsive to a current impulse for effecting an operation of said switch, a slow release control relay and a stick control relay at said second point and normally deenergized, means for energizing said control relays in response to operating the circuit controller to an active position, a stick circuit for said stick relay to retain said relay energized after the circuit controller is restored to its inactive position, control means controlled jointly by said two control relays and arranged to supply a control impulse to the line wires during the release period of said slow release relay for energizing the circuit means at said one point, indication means comprising two loop circuits each including a half-wave rectifier and a relay and adapted to receive current from the line wires but normally disconnected, indication means governed by the switch when operated to supply to the line wires an indicating impulse of current of either positive or negative polarity according to the position of the switch, means controlled by the stick relay when energized to connect the indication means with the line wires at the expiration of the control impulse, and means controlled by the relays of the indication means to indicate the position of the switch and to open the stick circuit in response to an indicating impulse.

14. A control system for railways including, two railway switches and two track sections at one point, a track circuit including a track relay for each track section, an operating means for each switch, a manually operated circuit controller for each switch and located at a second point, an indicator for each track section and located at the second point, a pair of line wires extending between the two points, two loop circuits normally connected with the line wires at the said one point and each including a half-wave rectifier and a relay, two loop circuits normally connected with the line wires at said second point and each including a half-wave rectifier and a relay, means controlled by the relays of the loop circuits at said one point to selectively govern the two operating means, means controlled by the relays of

the loop circuits at said second point to selectively govern the two indicators, means effective when one of the circuit controllers is operated to supply to the line wires an impulse of current of positive polarity to influence the corresponding loop circuit at said one point to operate one switch, means effective when the other circuit controller is operated to supply to the line wires an impulse of current of negative polarity to influence the other loop circuit at said one point to operate the other switch, means effective when one track relay is shunted to supply to the line wires current of positive polarity to energize the loop circuit at said second point to control one indicator, means effective when the other track relay is shunted to supply to the line wires current of negative polarity to energize the other loop circuit at the second point to control the other indicator, means effective when either circuit controller is operated to disconnect the loop circuits at said second point, and means effective when either track relay is shunted to disconnect the loop circuits at said one point.

15. A control system for railways including, a railway switch and a track section at one point, a track circuit including a track relay for the track section, an operating means for moving the switch, a manually operated circuit controller at a second point; a normal and a reverse switch indicator and a track indicator at said second point; a pair of line wires extending between said two points, a loop circuit normally connected with the line wires at said one point for controlling the operating means; an indication means for controlling said switch indicators and comprising two loop circuits each including a half-wave rectifier and a relay, and adapted to receive current from the line wires but normally disconnected; a third loop circuit at said second point for controlling the track indicator and normally connected with the line wires, control means effective in response to an operation of the circuit controller to disconnect said third loop circuit and to supply to the line wires a control impulse to energize the loop circuit at said one point to operate the switch; means governed by the control means to connect the indication means with said line wires at the termination of the control impulse, indication means governed by the switch when operated to supply to the line wires an indicating impulse of current of either positive or negative polarity according to the position of the switch to influence the corresponding loop circuit of the indication means to establish the corresponding switch indicator, and means effective when the track relay is shunted to disconnect the loop circuit at said one point and to supply to the line wires current to energize said third loop circuit to establish the track indicator.

16. A control system for railways including, a railway switch and a track section at one point, a track circuit including a track relay for the track section, a manually operated circuit controller at a second point, a pair of line wires extending between said two points, an operating means normally connected with the line wires at said one point and adapted to effect an operation of said switch in response to an impulse of current, an indication means normally connected with the line wires at said second point and adapted when energized to display an indication, control means at said second point to supply to the line wires a control impulse of current in response to an operation of said circuit controller to influence the operating means, means governed

by said circuit controller when operated to disconnect the indication means from said line wires during said control impulse, means controlled by the track relay in response to a train in said 5 track section to disconnect the operating means from said line wires and to supply to the line wires current for energizing the indication means to indicate at said second point the occupancy of the track section, and means governed by the indication means when energized to render the control means ineffective.
